UNITED STATES PATENT OFFICE.

JAMES H. SELLERS, OF OKLAHOMA, OKLAHOMA, ASSIGNOR TO THE NATIONAL SANITARY SERVICE COMPANY, OF OKLAHOMA, OKLAHOMA, A CORPORATION OF OKLAHOMA.

TOILET-PAPER DISPENSER.

1,383,245.

Specification of Letters Patent. Patented June 28, 1921.

Application filed July 1, 1918. Serial No. 242,864.

To all whom it may concern:

Be it known that I, JAMES H. SELLERS, a citizen of the United States, and a resident of the city, county, and State of Oklahoma, have invented a new and useful Invention in Toilet-Paper Dispenser, of which the following is a specification.

This invention relates to what is known in the art as a coin-controlled vending apparatus, and pertains particularly to a dispenser for lavatory accessories, especially toilet-paper, or toilet paper and an appendage for covering the lavatory seat.

It is an object of the invention to provide coin-controlled vending means for supplying toilet accessories.

Other objects of the invention will appear from a more complete reading of the following specification, claims, and drawing.

On the sheet of drawings, accompanying and forming a part of this specification,

Figure 1 is a side elevation view of the device incorporating the features of the invention,

Fig. 2 is a front view, fragmented, to show only the lower part of the machine, and,

Fig. 3 is a detailed, and enlarged view, showing the mechanism incorporated in said invention.

In these views, similar characters of reference indicate similar parts in the figures.

Journalized in the casing side walls 4 and 5 of a casing 6 is a shaft 7 upon which is mounted a member 8 provided with a plurality of shoes radially disposed, and which may be manually revolved, at will, by a knurled head 11 situated on the outer side of the casing 6 and upon the said shaft 7, when the coin controlled mechanism is released, as will be later explained.

Pivottally mounted at 12 within the casing is a two-way lever having arms 13 and 14, the extremity of one of which arms engages with a pin 15 carried by the member 8 and the other with radial lugs 16 borne on the periphery of said member 8. Thus when in normal position these levers holding against the lug 16 and pin 15 will lock the member against rotation until such time as will be later set forth.

To maintain this two way member in a normal position, a spring 17 is secured to one

of the levers or arms 14 and is secured also to a pin or stud 18 carried by a plate 19 mounted upon the shaft and which becomes a part of the casing 6.

Journalized at 20 in the side of the casing is a movably mounted lever 21 having an extended finger-piece 22 passing to the outside of the casing at the front to be operated after the introducing of a coin into the slot 23 which will appear later.

This lever is under the control of a spring 26 which holds it in an elevated position, and to this lever is journalized a trip 25 having a catch 24 to take over a pin 27 upon the arm 14 of the two way lever. This trip 25 is held in normal and locking position to the pin 27 by a spring 28 secured to the trip and to a stud 29 on the lever which in normal and locking position is just behind the stud 16 on the member 8, so that now this member is held in locked position by the arm 13 against stud 16, by the pin 29 behind the opposite stud 16 and by the end of lever arm 14 against the stud or pin 15.

When a coin 30 is dropped into the slot 23 and passes down the chute 31 for delivery into the coin box 32, which is locked inside of a door 33, this coin trips the trip 25 releasing the latch 24 from the pin 27. This will give liberty of movement to the spring 17 which changes the position of the two way lever so that both arms thereof free the stud 16 and pin 15. The lever 21 being depressed releases the pin 29 from the stud 16 and by use, now, of the head 11, the member 8 may be manually turned. The lever has been released to take a normal position, and while the turning of the member 8 takes place the upper pin 15 will ride on the face of the arm 14 and return it to a normal locking position, when the trip catch 24 will take the pin 27 on the arm 14 and again lock it for repeated operations, the reseating of the catch being also assisted by a leaf spring 34, borne by the trip and bearing against the underside of the lower lug 16 carried by member 8 as well as against the periphery of that member.

As the shoes 9 and 10 make their radial sweep they alternately come into contact with the article deposited in the magazine 34 and which rests on a shelf 35. This article may, of course, be any accessory and in the

present case is a folded package 36 the end of which is overturned as at 37 so that the shoe 9 or 10 can engage it and make a delivery along a chute not shown to the outside of the casing 6.

Having thus described this invention, I claim:

1. A device for dispensing packages comprising a rotary member, means carried by 10 said rotary member for engaging and delivering a package, a two-way member for controlling and releasing the rotary member, a lever adapted to lock said rotary member, and a coin operated trip mounted on said 15 lever adapted to normally hold said two-way member and said lever each in locking engagement with the rotary member.

2. In a coin controlled dispensing device, the combination of a rotary package dispensing member comprising a pivoted disk 20 having radial package engaging members and radial and face locking lugs, a locking member having two angularly disposed legs adapted to engage said radial and face locking lugs, respectively, a locking lever adapted 25 to engage said radial locking lugs, and a trip pivotally mounted on said lever adapted to normally engage said locking member and hold it and the locking lever both in locking engagement with said rotary member. 30

Signed at Oklahoma, in the county and State of Oklahoma, this 28 day of June, 1918.

JAMES H. SELLERS.
